(57) **CLAIM**

The ornamental design for a computer having a front bezel, as shown and described.

DESCRIPTION

FIG. 1 is a partial front perspective view of the design for the computer having a front bezel;

FIG. 2 is a front elevational view of the design for the computer having a front bezel as illustrated in FIG. 1;

FIG. 3 is a top elevational view of the design for the computer having a front bezel as illustrated in FIG. 1;

FIG. 4 is a partial front perspective view of a right portion of the design for the computer having a front bezel as illustrated in FIG. 1, wherein the left portion is substantially the same as the illustrated right portion;

FIG. 5 is a partial front elevational view of a right portion of the design for the computer having a front bezel as illustrated in FIG. 2, wherein the left portion is substantially the same as the illustrated right portion; and,

FIG. 6 is a partial top elevational view of a right portion of the design for the computer having a front bezel as illustrated in FIG. 3, wherein the left portion is substantially the same as the illustrated right portion.

In these drawings, the solid lines illustrate the claimed ornamental design, whereas the broken lines illustrate environmental features that form no part of the claimed ornamental design of the subject embodiments.
